UNITED STATES PATENT OFFICE.

CHARLES E. MULLINS, OF ROANOKE, ILLINOIS; ASSIGNOR TO JOHN T. BARROW, OF CHICAGO, ILLINOIS.

SCORING DEVICE FOR TILE-FORMING DIES.

Application filed April 30, 1921. Serial No. 465,638.

To all whom it may concern:

Be it known that I, CHARLES E. MULLINS, a citizen of the United States, having residence at Roanoke, in the county of Woodford and the State of Illinois, have invented certain new and useful Improvements in Scoring Devices for Tile-Forming Dies, of which the following is a specification, reference being had to the accompanying drawings, forming a part thereof.

This invention relates to a die for molding clay into the form of hollow tile building blocks or the like and its object is to provide such a die with a scoring device in which the portions, which are subjected to the most severe wear, are made removable for re-placement without the necessity of renewing the entire device. The invention consists in certain features and elements of the construction hereinafter described and shown in the drawings as indicated by the claims.

In the drawings:

Figure 1 is a front face view of a scoring device embodying this invention showing it removed from the die and viewed along the axis of movement of the clay which is fed through it in the tile molding process.

Figure 2 is a detail section taken as indicated at line 2—2 on Figure 1.

Figure 3 is a rear face view of the die dismounted from the auger mill or like machine on which it is used, but showing the scoring device associated with and secured to said die as it appears from the side at which the material emerges after the forming process.

Figure 4 is a transverse section taken as indicated at line 4—4 on Figure 3.

In the usual process of scoring brick and tile as it comes from the forming die a toothed metal frame or comb is employed which must be frequently renewed because of the rapid wear to which it is subjected on account of the friction of the granular though plastic mixture which is fed through it. Such replacement is expensive and requires scrapping a considerable weight of metal back of the wearing surfaces simply because the teeth are made integral with the supporting parts. The present construction, therefore, provides a separate frame member, 1, to which are added lining plates, 2, secured to its inner surfaces for contact with the plastic material; and for scoring

the tile the frame is fitted with a plurality of individual scoring teeth in the form of bolts, 3, each removably fitted into the frame, 1. Incidentally the bolts, 3, pass through the lining plates, 2, and thus serve to hold the latter in place.

In order to produce a grooving of the tile which is under-cut and thus tends to form an interlocking or dove-tailed engagement with the mortar when the tile is used in building construction, I prefer to use bolts of the flat-headed type in which the outer surface 3^a, of the head is at right angles to the axis of the bolt and is connected with the shank by a flaring frusto-conical portion, 3^b. While the frame, 1, might be provided with threaded apertures and the scoring teeth screwed in them I find it simpler to drill straight through the frame, and provide the bolts with nuts, 3^c, as shown.

As shown in Figures 3 and 4, the die which is chosen for purposes of illustrating this invention consists of a hollow body portion, 4, fitted with lining plates, 5, through which the plastic material is forced in the forming process. Cores, 6, are usually supported within the space enclosed by liners, 5, for producing a hollow block construction. At the outlet end of the die body, 4, from which the material emerges in the forming process the frame, 1, is secured in place with its opening registering with that of the die. Preferably the frame is formed so that its lining plates, 2, stand in planes oblique to the axis of movement of material thus providing surfaces which converge in the direction of such movement for the purpose of slightly compressing the tile in this final step of its formation.

The scoring teeth consisting of bolts, 3, however are set with their axes perpendicular to the direction of movement so that the planes of their flat heads, 3^a, are parallel to said direction and the result is that the grooves cut in the surface of the tile by these scoring teeth are slightly reduced in depth by a further compression of the upstanding ridges of the material between the grooves as it encounters the converging surfaces, 2^a, of the lining plates, 2, after leaving the scoring teeth. This tends to increase the undercut effect produced in the grooves by the conical shape of the heads of the bolts, 3, and has some further effects which are more fully dis-

cussed in my application on the scoring process as such. Preferably, in setting the bolts, 3, in the frame, 1, I arrange them so that the slots, 3^a, in the heads will extend 5 transversely of the direction of feed of material through the die to avoid marking the tile by the slots.

I claim:

1. In a die for molding tile and the like 10 means for scoring the surface of the tile comprising a frame having an opening which approximates the cross sectional outline of the tile to be formed and is bounded by surfaces converging in the direction of movement of the material therethrough and scoring teeth projecting from said converging surfaces, said teeth being of greater cross section at a distance from said surfaces than 15 at planes thereof in order to form undercut 20 grooves in the material passed through the frame.

2. In the combination defined in claim 1 said scoring teeth being of frusto-conical 25 form set in the frame with their axes substantially perpendicular to the general direction of movement of material through the frame and therefore oblique to the converging surfaces thereof.

3. In the combination defined in claim 1 30 the width of said scoring members measured transversely of the direction of movement of the material being graduated with the widest part intermediate the respective portions with which the material first contacts and 35 from which it recedes.

4. In the combination defined in claim 1 40 a set of removable lining plates secured to the frame and forming the said converging surfaces from which the scoring members project.

5. In the combination defined in claim 1 45 said scoring teeth being bolts with the under surfaces of their heads of frusto-conical form, the frame being drilled to receive the shanks of said bolts leaving the heads projecting from its converging surface.

6. In the combination defined in claim 1 50 said scoring teeth being bolts with the under surfaces of their heads of frusto-conical form, the frame being drilled to receive the shanks of said bolts leaving the heads projecting from its converging surfaces, the threaded ends of such shanks projecting through the frame and securing nuts applied

thereto for holding the parts in assembled 55 relation.

7. In the combination defined in claim 2 the scoring teeth being flat headed bolts having slots in their flat head surfaces extending 60 transversely of the direction of feed of the material through the frame.

8. In combination with a die for molding tile and the like means for scoring the surface of the tile comprising a frame associated with the die and a plurality of individual scoring teeth removably mounted in the frame lining plates, removably secured to the frame providing surfaces for contact with material passed through the die, said scoring teeth being set through the lining plates into the frame and having enlarged portions which project from the exposed surfaces of said plate in position to score material passing through the frame and also to secure said lining plates to the latter. 75

9. In a die for molding tile and the like, means for scoring the surface of the tile comprising an opening which approximates the cross-sectional outline of the tile to be formed, said opening being bounded by surfaces which converge in the direction of movement of the material therethrough and a plurality of scoring teeth each projecting from one of said surfaces and being of greater cross-section at a distance from the surface than at the plane thereof; the converging portions of said surfaces extending beyond such teeth in the direction of movement of the material through such die. 80

10. In a die for molding tile and the like 90 an opening which approximates the cross-sectional outline of the tile to be made, said opening being formed by lining plates removably associated with the die and arranged with their surfaces which form the 95 opening converging in the direction of movement of the tile therethrough together with bolts having heads of frusto-conical form set through said lining plates with their conical surfaces spaced therefrom whereby 100 said heads will serve as scoring teeth for grooving the surface of the tile as the latter is forced through the opening.

In testimony whereof, I have hereunto set my hand at Roanoke, Illinois, this 26 day of April, 1921.

CHARLES E. MULLINS.
